APPARATUS FOR DRYING MATERIAL BY
UTILIZING VAPOR HEAT

Rudolf Bernstein, Zurich, Switzerland

Application June 25, 1940, Serial No. 342,391
In Switzerland October 21, 1937

1 Claim. (Cl. 34—86)

It has already been proposed to use drying apparatus with tunnel-like chambers in which the material is dried by utilizing vapor heat. The external air can enter freely into the tunnel, and at that place in the tunnel where it has presumably acquired the maximum moisture it is passed into a heat exchanger for the purpose of supplying drying heat. The transmission of heat to the material to be dried occurs through the air in the tunnel which is circulated a number of times.

Such an arrangement has the disadvantage that the quality of air which is passed over the heat exchanger through which the vapor flows and over the material to be dried, is too small in comparison with the air and vapor mixture simultaneously passing through the heat exchanger to be able to transmit a sufficient amount of heat in the vapor to the material to be dried.

The present invention relates to a method of and an arrangement for drying material by utilizing vapor heat, whereby the aforementioned disadvantages are overcome as a result of the drying air being brought, in a first drying section by means of external heat and due to receiving water from the material to be dried, to approximately such a high dew point as the material to be dried will allow and being passed practically saturated through heat exchangers in at least one further drying section while fresh air is forced over the heat exchangers and the material to be dried, said drying air being by weight at least 50 times as large as the quantity of water which, during the same time in the first drying section, is absorbed by the drying air as vapor and passed to the heat exchangers of the next drying section.

The invention is described in connection with the accompanying drawings, in which,

Fig. 1 is a diagrammatic illustration of an apparatus consisting of two drying chambers,

Fig. 2 is a diagrammatic illustration of an apparatus consisting of three drying chambers,

Fig. 3 shows an arrangement with two drying chambers in vertical longitudinal section,

Fig. 4 shows a horizontal section of an arrangement with two drying chambers;

Fig. 5 shows a cross section on the line IV—IV in Fig. 3,

Fig. 6 shows an arrangement with three drying chambers in longitudinal section, and

Fig. 7 shows a cross-section on the line V—V in Fig. 6.

In Fig. 1 the material *a* to be dried is divided between the two chambers I and II, one of which

5 has an external source of heat *l*. Fresh air enters chamber I at *p*; this is circulated a large number of times by the ventilator *u*, driven by the motor *j*, and passes, mixed together with the hot vapors in chamber I, through pipe *q* into the heat exchanger *i* of chamber II and heats the air inside chamber II which is mixed with additional fresh air entering at *s*. At the same time it is possible to supply each chamber I and II with fresh material and to complete the drying in the same chamber; alternatively the material can be given a preliminary drying in either chamber I or II and the remaining moisture is then extracted in chamber II or I. The final mixture of vapor and air passes to the atmosphere at *r*.

10 The ratio of the quantity of air flowing inside the heat exchangers to that outside of same, which it is preferable to adhere to and which differs very considerably from previous values, is calculated as follows:

15 If for instance in chamber I with the external source of heat, a practically saturated vapor-air mixture with a dew point of 70° C. is produced and this is passed into the heat exchanger of chamber II which is heated by vapor, the rise in temperature of the air in the drying space there can be restricted to 40° C. if about six times as much air is blown through it as goes through the heat exchanger during the same interval of time.

20 For 1 kilogram vapor with a dew point of 70° C. there should be about 3½ kilograms of air; at 40° C. however, about 20 kilograms of air, that is to say about six times as much as with a dew point of 70° C.

25 When it is desired to utilize the heating medium from a dew point of 70° C. down to a temperature of about 40°, approximately 170 calories must be extracted from each kilogram of air contained in it and this transmitted by means of the drying air to the material to be dried. Since,

30 however, owing to the temperature difference which exists between the heating medium and the drying air, it is not an advantage to warm the drying air on an average more than 15° C., that is 1 kilogram of this air absorbs during one contact with the heating elements approximately 3.6 calories, therefore 1 kilogram of heating air must be brought into contact with $170 : 3.6 = 47$ kilograms of drying air in the heat exchangers.

35 If the heating medium passes with a dew point of 80° C. into the heating element, then because the available quantity of heat is considerably higher than before the quantity of drying air must be correspondingly increased when it is desired to utilize completely the available heat.

Since the heat content of the heating medium is mainly determined by the amount of water vapor contained therein, the necessary quantity of drying air is preferably fixed in accordance with this. Therefore in order to utilize fully a heating medium having a dew point of 70° C. it would be necessary to have by weight 200 times as much drying air as the water vapor which passes with the heating medium into the heating element. An economic minimum is considered to be 50 times the quantity.

The method described in connection with the example illustrated in Fig. 1 enables practically all the heat stored in the vapor of the drying section with the external heat source to be re-utilized once. A further saving in external heat is possible if, in a known manner, the air-vapor mixture taken from the drying chamber I with the external heating is, as shown in Fig. 2, first passed through heat exchanger *i'* of the drying chamber II' from which latter the fresh air supply for chamber I is taken. If for instance, the dew point of this air is forced up to 80° C. by means of additional heat, part of its heat which is liberated between 80° C. and 70° C. by condensation of the water vapor contained therein can be utilized in the third drying chamber II' where the material to be dried is comparatively cool.

What has up to the present been overlooked is that in this case it is necessary to provide a very strong air circulation, because the amount of air driven through the drying chamber II' is the same as that in the heating medium in the tubes *i'* and therefore considerably smaller than that in chamber II. Furthermore the temperature differences in chamber II' are much smaller than in chamber II because it is desired to obtain here as high a dew point as possible in order to reduce to a minimum the amount of external heat required.

In the constructional example illustrated in Figs. 3-5 the material *a* to be dried, for instance grass, is brought in the direction of the arrow on to an endless conveyor band *b* which transports it to *d* where it falls down the wall *e* on to a second conveyor band *f* which transfers it to *h*, where it is expelled from the dryer.

On the conveyor band *b* the material to be dried passes through the channel *c* which contains the heating elements *i*. The conveyor band *f* moves the material to be dried through the channel *g* in which the heating elements *k* are located. The channel *g* is the second drying chamber and is heated from an external source of heat by supplying the heating elements *k* through the pipe *l* with live steam, hot water or the like. The heating medium emerges at *m* and *n*. The moist air produced in channel *g* passes through the heat exchangers *i* in the channel *c*, in the first drying chamber. This air has entered the channel *g* at *p*₁ and *p*₂ as dry air and is sucked in the form of moist air out of the middle of the channel *g* by means of a small fan *o*, which conveys it through the pipe *q* into the heat exchangers *i*. The heating air and condensed water flow out through the pipes *t*₁ and *t*₂. In addition the fan *r*, which is very large by comparison with fan *o*, withdraws air from the middle of the channel *c* and conveys it to the atmosphere; this air enters channel *c* at *s*₁ and *s*₂.

As can be seen from Figs. 4 and 5 the air which flows through *c* is strongly circulated by means of a ventilator wheel of special construction. In channel *c* there is a ventilator wheel *u* arranged next to the conveyor *b* and extending along the

whole length of the channel. This ventilator operates like a so-called drum type blower and circulates the air in a manner indicated by the arrows in Fig. 5, so that the air whilst it passes through the channel *c* is circulated a large number of times between the material to be dried and the heat exchangers *i*.

In the constructional example described, the air and vapor mixture from the drying chamber *g*, which is heated from an external source, after its dew point has been raised by heating as high as the material to be dried will allow (for instance for grass 80° C.), is forced through the heat exchanger *i* of the second drying chamber *e*. In this drying chamber the air is recirculated from the heat exchangers *i* to the material to be dried so many times by means of the ventilator *u* that the amount of recirculated air by weight is at least 50 times as great as the amount of vapor contained in the air and vapor mixture passing through the tubes *i* during the same interval of time.

It is permissible also to circulate the air in channel *g* in a similar manner, although there the temperature difference between heating elements and the material to be dried may be many times greater than that in channel *c*, so that the air circulation need not be made so strong.

With the three-section drying arrangement illustrated in Figs. 6 and 7, the material to be dried, *l* is thrown on to the conveyor band *2* in the direction shown by the arrow, where it is transported up a slope into channel *4*, closed at the upper end, and from there by conveyor band *3* to the lower end where it falls on to conveyor *10* which conveys it through channel *11*, which is open at both ends, to be expelled at *13*. The upper end of channel *4* contains the heating elements *9* which are supplied with live steam or the like. Below these are the elongated heating boxes *6* which act as heat exchangers and are clearly shown in Fig. 6. These boxes are fed with moist air taken from the highest point of channel *4* and passed through pipe *5*. After condensation of a certain amount of water, the air which still contains a large amount of vapor passes through pipe *7* into the heat-exchanging heating boxes *8* shown in the section in Fig. 7. The condensate can be collected in a steam trap not shown in the drawings. Both channel *4* and channel *11* are powerfully cross ventilated by drum type blowers *14* and *15*, exactly in the same way as channel *c* in Fig. 5. At the same time by means of inclined surfaces on the blowers or in the path of the circulating air, this latter receives the required motion in a longitudinal direction through the channels. The air and vapor mixture can be drawn through the heating boxes *6* and *8* by means of the small fan *12*.

The amount of free air entering and leaving the drying chambers is preferably selected to correspond with the dew point which it is desired to attain and the amount of heat transmitting air is determined by the choice of the speed of circulation of same. The quantity of air driven through and its speed of circulation in the different drying chambers can be so selected that dew points result which, due consideration being given to the available heating surfaces at each place, the average heating temperature and the circulating quantity of dry air, enable for each drying section the intended utilization of the heat in the vapor to be achieved.

I claim:

75 Apparatus for drying materials comprising a

first drying chamber, a second drying chamber and a third drying chamber, a heater in the first drying chamber, a source of external heat, means for delivering heat from said external source to said heater, a first heat exchanger in the second drying chamber, a second heat exchanger in the third drying chamber, said first and second heat exchangers being connected in series, said first and second drying chambers forming an upwardly sloping channel closed at the top with the first drying chamber at the higher level, means for passing air through said first drying chamber, means for withdrawing air and vapor mixture from said first drying chamber at its highest point and passing it through said heat exchangers, an upper conveyor band in said

channel for conveying material to be dried to and through said first drying chamber, a lower conveyor band for conveying material from said first drying chamber to and through said second drying chamber, a third conveyor band for conveying material delivered by said lower conveyor band through said third drying chamber and means for circulating air through said second and third drying chambers, said last named means being capable of contacting at least 50 times as much air by weight with the material to be dried as is the weight of vapor which passes from said first drying chamber to said heat exchangers in the same interval of time.

RUDOLF BERNSTEIN.
